CLAIM

The ornamental design for a creeper, as shown and described.

DESCRIPTION

FIG. 1 is a top, rear, left side perspective view of a creeper showing our new design;
FIG. 2 is a top plan view thereof;
FIG. 3 is a bottom plan view thereof;
FIG. 4 is a right side elevational view thereof, the left side being a mirror image of FIG. 4;
FIG. 5 is a front elevational view thereof; and,
FIG. 6 is a rear elevational view thereof.
FIG. 7 is a bottom plan view of a second embodiment of the creeper;
FIG. 8 is a right side elevational view of FIG. 7, the left side being a mirror image of that shown, and all other views of this embodiment being the same as FIGS. 1, 2, 5 and 6;
FIG. 9 is a bottom plan view of a third embodiment of the creeper;
FIG. 10 is a right side elevational view of FIG. 9, the left side being a mirror image of that shown, and all other views of this embodiment being the same as FIGS. 1, 2, 5 and 6;
FIG. 11 is a top plan view of a fourth embodiment of the creeper;
FIG. 12 is a bottom plan view of FIG. 11;
FIG. 13 is a right side elevational view of FIG. 11, the left side being a mirror image of that shown;
FIG. 14 is a front elevational view of FIG. 11;
FIG. 15 is a rear elevational view of FIG. 11;
FIG. 16 is a bottom plan view of a fifth embodiment of the creeper;
FIG. 17 is a right elevational view of FIG. 16, the left side being a mirror image of that shown, and all other view of this embodiment being the same as FIGS. 11, 14 and 15;
FIG. 18 is a bottom plan view of sixth embodiment of the creeper; and,
FIG. 19 is a right side elevational view of FIG. 18, the left side being a mirror image of that shown, and all other views of this embodiment being the same as FIGS. 11, 14 and 15.
